By Charles G. Cope
Atty.

UNITED STATES PATENT OFFICE.

FRANK R. BELLUCHE, OF MANSFIELD, MASSACHUSETTS, ASSIGNOR, BY MESNE ASSIGNMENTS, TO MILLER SAW-TRIMMER COMPANY, OF PITTSBURGH, PENNSYLVANIA, A CORPORATION OF PENNSYLVANIA.

MECHANICAL MOVEMENT.

Application filed December 14, 1925. Serial No. 75,166.

My invention pertains to mechanical movements, and relates especially to mechanical movements of the general character employed in bed motions for printing presses such as that described in Letters Patent No. 1,398,817, granted November 29, 1921, to Burt F. Upham and myself or such mechanical movements as are described in the co-pending application of Burt F. Upham filed 10 of even date herewith.

It is the principal object of my invention to improve upon mechanical movements of the general kind disclosed in the said Patent No. 1,398,817, by simplifying the guard shoe 15 construction and eliminating the necessity for guard rolls in addition to the reversing wrist pins. Other objects will appear from the following description taken in connection with the claims annexed thereto.

20 My improvements are embodied in the mechanical movement described, by way of example, in the following specification, and shown in the accompanying drawings, in which:

25 Fig. 1 is a partial side elevation of a bed and cylinder printing press embodying my present invention as a means for effecting the reciprocation of the type-bed, the latter being shown in one of its extreme end positions;

30 Fig. 2 is a sectional end view, the section being taken on the line 2—2 of Fig. 1;

Fig. 3 is a sectional elevation, taken on the line 3—3 of Fig. 2, looking in the direction of the arrows, the parts, however, being 35 shown in the position in which the type-bed has just concluded its uniform movement towards the right and is just about to be slowed down prior to reversal;

Fig. 4 is a section on the line 4—4 of Fig. 40 3, looking in the direction of the arrows;

Fig. 5 is a perspective view of one of the wrist pins;

Fig. 6 is a detail section taken on the line 6—6 of Fig. 3;

45 Fig. 7 is a section on the line 7—7 of Fig. 6, looking towards the right;

Fig. 8 is a similar section but looking towards the left; and

50 Fig. 9 is a diagram illustrating the manner of operation of the guard heads with which the wrist pins are provided.

The press comprises a pair of main side frames 10 and 11 carrying between them sub-frames 12 and 13. At the upper edges of the

latter are formed tracks for the reception of 55 rolls 14, and upon these latter the bed 15 runs in the well known manner. To the underside of the bed are secured a pair of racks 16 and 17, one on each side of the longitudinal center line of the bed. One of 60 these racks is utilized in effecting the uniform movement of the bed in one direction, the other being utilized for effecting such uniform movement in the opposite direction. The non-uniform movements of the bed, in 65 stopping, reversing and starting in the opposite direction, are effected by reversing rolls mounted on wrist pins carried by reversing wheels, such wrist pins engaging reversing shoes formed upon a hanger 18 centrally disposed with respect to the bed and extending 70 downwardly from the latter.

A main drive shaft 19 (Figs. 1 and 2) is mounted in suitable bearings carried by the sub-frames 12 and 13 and has secured thereto a pinion 20 which meshes with a gear 21 secured to a shaft 22. The latter is mounted in a large bearing 23 carried by the sub-frame 12 and extends outward through the side frame 10, having secured thereto, at its 80 outer end, a large gear 24. The latter meshes with the gear 25 of the impression cylinder 26. The gears 24 and 25 are of the same diameter, so that the cylinder rotates uniformly with the gear 21.

85 A stub shaft 27 (Figs. 1 to 4) is mounted in a bearing of the sub-frame 12 and carries the right-hand reversing wheel 28, which is a gear wheel of the same diameter as, and meshing with, the gear 21. The wheel 28 90 is termed the right-hand reversing wheel because it carries a wrist pin and reversing roll, and effects the slowing down, reversing and restarting of the bed at the right-hand end of the travel of the latter.

95 Mounted on a stub shaft 29 carried by a bearing of the sub-frame 12, and longitudinally movable on such shaft, is the left-hand bed-driving pinion 30, so called because it effects the uniform movement of the type bed in the left-hand direction. This pinion 30 meshes continuously with the teeth of the reversing wheel 28, but, by longitudinal movement on its shaft 29, it can be moved into and out of operative relation with the 100 bed rack 16.

The left-hand reversing wheel 31 is carried by a stub shaft 32 of the sub-frame 13

and is a gear wheel of the same diameter as the right hand reversing wheel 28 and gear 21. It is driven by a pinion 33 on the main drive shaft 19, this pinion being of the same diameter as the pinion 20 which drives the gear 21. With the teeth of the wheel 31 meshes the right-hand bed-driving pinion 34, which is mounted on a stub shaft 35 carried by a bearing of the sub-frame 13. This pinion is longitudinally movable upon a shaft, into and out of operative relation with the bed rack 17.

The bed racks 16 and 17 are of a length equal to one-half the pitch circumferences 15 of the reversing wheels 28, 31; and, from this and the preceding description of the gearing, it will be understood that the press now being described is of the two revolution type, having what is known as the two to 20 one bed motion.

Secured to the shaft 22, on the outside of the frame 10, is a pinion 36 which engages with a gear 37 carried by the cam shaft 38. The gear 37 is twice the diameter of the 25 pinion 36; so that the cam shaft makes one revolution for each cycle of the press. Upon the shaft 38 is secured a cam 39 having a groove 40 in which engages a roller carried by the lower end of a cam lever 41. The cam 30 lever 41 is pivoted to the sub-frame 13 (Figs. 3 and 4) and has pivoted thereto, at its upper end, a block which engages in a channel 42 formed in the hub of the right-hand bed-driving pinion 34. Pivoted to the 35 sub-frame 12, and connected to the lower end of the cam lever 41 by a link 43, is a second cam lever 44 having pivoted to its upper end a block which engages a channel 45 of the left-hand bed-driving pinion 30. 40 The groove 40 of the cam 39 is such that the cam levers 41, 44, will be moved transversely to the right (Fig. 4) during one quarter, held stationary during the next quarter, moved to the left during the next quarter, and held stationary during the last quarter, of the cycle.

In the position of the parts shown in Figs. 3 and 4, the cam 39 has held the right hand bed driving pinion 34 in engagement with 50 the bed rack 17 for a quarter cycle of the press, which is a one half revolution of the left-hand reversing wheel 31, and has held the left-hand bed-driving pinion 30 out of engagement with the bed rack 16 during this 55 period. Thus the bed has just been given a uniform movement equal to one half the pitch circumference of the reversing wheel. At this point the rack 17 leaves the pinion 34 lengthwise. During the next quarter 60 cycle, during which the racks 16 and 17 are out of engagement with the pinions 30 and 34 and the reversing operation is taking place, the cam 39 will shift the pinions 30 and 34 to the left, thus moving the pinion 34 out of the path of the rack 17, and bring-

ing the pinion 30 into the path of the rack 16 so as to be ready to impart the uniform movement to the bed after the reverse has been completed.

Each of the reversing wheels carries a 70 wrist pin on which is mounted a reversing roll for engaging the shoes carried by the hanger 18 of the bed. Taking the right-hand reversing wheel 28,—one of its spokes is enlarged so as to form a bearing 51 in 75 which is keyed the shank 46 of a wrist pin 47, the latter being held in place in the bearing by a nut 48 (Figs. 5 and 6). Upon the wrist pin is revolvably mounted a reversing roll 49, the latter being held in place by 80 a guard head 50 on the wrist pin, which head confines the roll between itself and the face of the bearing 51. The guard head 50 is of segment shape, having an arc-shaped face 58 and a flat face 59, the segment being less 85 than one half of a circle which is of the same diameter as the roll 49. The left-hand reversing wheel is provided with a similarly arranged wrist pin having a similar segment-shaped guard head 50^a and carrying 90 a reversing roll 49^a. The reversing rolls co-operate with reversing shoes which are set at an angle of 45° to the plane of movement of the bed; so that the wrist pins must be located within the pitch line of the reversing 95 wheels.

The hanger 18 of the bed is formed, on its front face, and on the left-hand side of its center, with a flange 52 disposed at an angle of 45° to the vertical. This flange is of a depth somewhat greater than the combined widths of the reversing roll 49 and guard head 50. Secured to the face of the flange 52 is an effective shoe 53 of a width only equal to that of the roll 49; so that the shoe 100 will be engaged by the reversing roll 49, but will not be engaged by the guard head 50. The hanger 18 is also formed with a second flange 54 parallel with the flange 52, the said flange being of a depth equal to that of the flange 52 for a short distance at the top end, but being narrow for the remainder of its length. To the flange 54 is secured a guard shoe, at the top end of which is a portion 105 55 of a width equal to the combined widths 110 of the reversing roll 49 and guard head 50, the remaining part 56 of the guard shoe being of a width only equal to that of the guard head 50. Thus the effective shoe 53 can never be engaged by the guard head 50, while the narrow lower part 56 of the guard shoe can never be engaged by the reversing roll 49. The effective shoe 53 and the guard shoe are spaced apart by a distance equal to 115 the diameter of the reversing roll 49, and form between them what may be termed the right-hand reversing channel 57. At its left-hand end, and on its rear face, the hanger 120 18 is formed with flanges and provided with shoes similar to those above described, such 125 130

shoes forming between them what may be termed the left-hand reversing channel 57^a.

Referring now to Fig. 3, this figure shows the parts just as the bed rack 17 is leaving the right-hand bed-driving pinion 34. At this time the effective shoe 53 will have arrived in contact with the reversing roll 49, which latter will be just entering upward between such shoe and the upper portion 55 of the guard shoe. Supposing the press to be operating at speed, the momentum of the bed, which has just finished its uniform movement towards the right, will crowd the effective shoe 53 against the reversing roll 49. As the reversing roll moves from the point *a* to the point *b* (Fig. 9), the bed will be gradually retarded by the reversing roll, and finally stopped when the point *b* is reached. During this time the reversing roll travels upward and then downward in the channel 57 between the effective shoe 53 and the upper portion 55 of the guard shoe. As the reversing roll passes from the point *b* to the point *c*, it will operate upon the effective shoe 53 to force the bed to the left, until, when the point *c* is reached, the correct face speed for the uniform movement of the bed will have been attained. At this point the left-hand bed-driving pinion 30 will be engaged by the bed rack 16 and will thereafter drive the bed.

When the press is being turned over slowly by hand, the bed will, of course, have no such momentum as would complete its movement after the rack has left the bed-driving pinion. In that case, the reversing roll 49, by its engagement with the upper portion 55 of the guard shoe, effects the completion of the movement of the bed.

The guard heads 50 and 50^a of the wrist pins have no effect during the ordinary running of the bed at speed, since, under these conditions, the pressure is always between the effective shoes and the reversing rolls, and these effective shoes are not wide enough to be contacted by the curved faces 58 of the guard heads. The prime purpose of these guard heads is to prevent accidental movement of the bed out of its proper position with respect to the reversing rolls, to prevent overrunning of the bed during starting, and to enable the press to be turned over in a reverse direction when desired. The manner in which the guard heads operate will be understood from the diagram, Fig. 9. In the full-line position indicated at *h* in this diagram the reversing shoes, during the uniform movement of the bed towards the right, are approaching the wrist pin 47, which is moving upward in its travel. It will be observed that if the lower part 56 of the guard shoe were of full height, it would collide with the reversing roll. However, this part of the guard shoe being only of a height equal to the width of the guard

head 50, the flat side 59 of the latter can enter beneath the end of the shoe. The position indicated by *i* shows how the flat side of the guard head thus enters beneath the shoe 56. In the position indicated at *a*, the reversing roll has started to operate, but the curved edge 58 of the guard head is not operative because the effective shoe is not wide enough to be engaged by it. In the position indicated at *b* the reversing roll is just leaving the space between the effective shoe and the wide part 55 of the guard shoe, and it will be seen that the curved face 58 of the guard head is in position to engage the narrow part 56 of the guard shoe. In the position indicated at *c*, which is the position at which the uniform movement of the bed starts, the curved face 58 of the guard head is still in position to be engaged by the narrow part 56 of the guard shoe, but is just about to leave the same in a downward direction.

The only time when the bed would be otherwise out of control is during the travel of the wrist pins between the points *b* to the points *c*. During this time, the bed is held in its proper relative position with respect to the wrist pins by the guard heads, which are at that time in a position to be engaged by the narrow portions 56 of the guard shoes. If it is desired to turn the press in a reverse direction, the bed is carried over the space during which the wrist pins move from the points *c* to the points *b* by the driving action of the curved faces 58 of the guard heads upon the narrow portions 56 of the guard shoes.

By the cutaway guard heads of the present invention I am enabled to reduce materially the cost of manufacture of a movement of this character by obviating the necessity of extra rolls, specially curved guard shoes, and the like. At the same time I am enabled to retain the advantages of a construction which employs no movable gates.

Having thus fully described my invention, what I claim as new, and desire to secure by Letters Patent, is:

1. In a mechanical movement, a reciprocable body, an effective shoe and a guard shoe carried by said body, rotary means cooperating with said effective shoe for reversing the movement of said body, and a guard head having a curved portion for cooperation with said guard shoe, said guard head being reduced at one part to permit its entry with respect to said guard shoe.

2. In a mechanical movement, a reciprocable body, an effective shoe and a guard shoe carried by said body, said shoes being disposed at an angle of less than 90° to the plane of reciprocation of said body, rotary means cooperating with said effective shoe for reversing the movement of said body, and a guard head having a curved portion

for cooperation with said guard shoe, said guard head being reduced at one part to permit its entry with respect to said guard shoe.

5. In a mechanical movement, a reciprocable body, an effective shoe and a guard shoe carried by said body, said shoes being parallel and disposed at an angle of less than 90° to the plane of reciprocation of said body, rotary means cooperating with said effective shoe for reversing the movement of said body, and a guard head having a curved portion for cooperation with said guard shoe, said guard head being reduced at one part to permit its entry with respect to said guard shoe.

6. In a mechanical movement, a reciprocable body, an effective shoe and a guard shoe carried by said body, said guard shoe being of less height than said effective shoe, rotary means cooperating with said effective shoe for reversing the movement of said body, and a guard head having a curved portion for cooperation with said guard shoe, said guard head being reduced at one part to permit its entry with respect to said guard shoe.

7. In a mechanical movement, a reciprocable body, an effective shoe and a guard shoe carried by said body, said shoes being disposed at an angle of less than 90° to the plane of reciprocation of said body and said guard shoe being of less height than said effective shoe, rotary means cooperating with said effective shoe for reversing the movement of said body, and a guard head having a curved portion for cooperation with said guard shoe, said guard head being reduced at one part to permit its entry with respect to said guard shoe.

8. In a mechanical movement, a reciprocable body, an effective shoe carried by said body and disposed at an angle of less than 90° to the plane of reciprocation of said body, a guard shoe carried by said body and disposed parallel with said effective shoe, said guard shoe having a portion of substantially equal height to that of said effective shoe, and having a portion of less height than that of said effective shoe, rotary means cooperating with said effective shoe and with the higher portion of said guard shoe for reversing the movement of said body, and a guard head having a curved portion for cooperation with the narrow portion of said guard shoe, said guard head being reduced at one part to permit its entry with respect to said guard shoe.

9. In a mechanical movement, a reciprocable body, an effective shoe and a guard shoe carried by said body, said shoes being disposed at an angle of less than 90° to the plane of reciprocation of said body, a reversing wheel, and a wrist pin carried by said wheel and cooperating with said effective

shoe to reverse the movement of said body, said wrist pin being provided with a guard head having a curved portion for cooperation with said guard shoe and being reduced at one part to permit its entry with respect to said guard shoe.

10. In a mechanical movement, a reciprocable body, an effective shoe carried by said body and disposed at an angle of less than 90° to the plane of reciprocation of said body, a guard shoe carried by said body and disposed parallel with said effective shoe, said guard shoe having a portion of substantially equal height to that of said effective shoe, and having a portion of less height than that of said effective shoe, a reversing wheel, and a wrist pin cooperating with said effective shoe and the higher portion of said guard shoe for reversing the movement of said body, said wrist pin being formed with a guard head having a curved portion for cooperation with the narrow portion of said guard shoe, said guard head being reduced at one part to permit its entry with respect to said guard shoe.

11. In a mechanical movement, a reciprocable body, a reversing wheel, a reversing member carried by said wheel, a guard head carried by said wheel and disposed concentrically with said reversing member, said guard head being reduced at one part, an effective reversing shoe for cooperation with said reversing member, said shoe being carried by said body, and a guard shoe carried by said body for cooperation with said guard head, said guard shoe being disposed out of the path of said reversing member.

12. In a mechanical movement, a reciprocable body, a reversing wheel, a reversing member carried by said wheel, a guard head carried by said wheel and disposed concentrically with said reversing member, said guard head being reduced at one part, an effective reversing shoe for cooperation with said reversing member, said shoe being carried by said body and disposed at an angle of less than 90° to the plane of reciprocation of the latter, and a guard shoe carried by said body for cooperation with said guard head, said guard shoe being disposed out of the path of said reversing member.

13. In a mechanical movement, a reciprocable body, a reversing wheel, a reversing member carried by said wheel, a guard head carried by said wheel and disposed concentrically with said reversing member, said guard head being reduced at one part, an effective reversing shoe for cooperation with said reversing member, said shoe being carried by said body and disposed at an angle of less than 90° to the plane of reciprocation of the latter, and a guard shoe carried by said body for cooperation with said guard head, said effective shoe being disposed out of the path of said guard head, and said

guard shoe being disposed out of the path of said reversing member.

12. In a mechanical movement, a recipro-
cable body, a reversing wheel, a reversing
member carried by said wheel, a guard head
carried by said wheel and disposed concen-
trically with said reversing member, said
guard head being reduced at one part, an
effective reversing shoe for cooperation with
10 said reversing member, said shoe being car-
ried by said body and disposed at an angle

of less than 90° to the plane of reciprocation
of the latter, and a guard shoe carried by
said body, said guard shoe having a portion
for cooperation with said reversing member 15
and a second portion for cooperation with
said guard head, said effective shoe being
disposed out of the path of said guard head,
and said second portion of said guard shoe
being disposed out of the path of said re- 20
versing member.

FRANK R. BELLUCHE.
